—INVENTOR:—

Joseph Bevan.

BY *Drake & Co.* ATT'YS.

UNITED STATES PATENT OFFICE.

JOSEPH BEVAN, OF NEWARK, NEW JERSEY.

DESIGN FOR A SADDLE-TREE.

SPECIFICATION forming part of Design No. 16,976, dated November 9, 1886.

Application filed August 20, 1886. Serial No. 211,442. Term of patent 14 years.

To all whom it may concern:

Be it known that I, JOSEPH BEVAN, a citizen of the United States, residing at Newark, in the county of Essex and State of New Jersey, have invented and produced a new and original Design for Saddle-Trees; and I do hereby declare the following to be a full, clear, and exact description of the invention, such as will enable others skilled in the art to which it appertains to make and use the same, reference being had to the accompanying drawing, and to letters of reference marked thereon, which form a part of this specification.

The figure is a side elevation, slightly in perspective, of my newly-designed saddle tree, one view being deemed sufficient to illustrate the design.

The leading feature of my design consists in a saddle-tree having the peculiar configuration hereinafter set forth, and finally embodied in the clause of the claim.

In said drawing, *a* indicates the pommel, the front edge, *b*, of which, when viewed in side elevation, presents a straight vertical outline, which extends to a "burr," *c*, where the edge is rounded outwardly or forwardly and downwardly, as at *d*, and an angle being formed at *e*, where the vertical and outwardly-curved lines join or come together. The central longitudinal line, *p*, at the top of the pommel extends backward and downwardly, as shown, from the vertical front line, *b*, to the end of the slot, and does not rise upwardly and then forwardly as in saddles having a horn above the pommel. The line *d* curves backwardly at *f* and upwardly at *g*, approaching nearly a vertical line at this point, and at *h* again curves downwardly and backwardly to *i* near

the back of the tree, where it gives another upward turn, as at *j*, and finally a forward turn, as at *k*, terminating beneath the cantle, the line forming an angle, *e*, at the base of the pommel with the straight vertical line *b* being a series of continuous curves to the point *k*. The upper edge of the cantle presents a continuous simple curve from *l* to a corresponding point on the opposite side of the saddle.

The edge *n* at the center slot, *o*, of the saddle-tree, when viewed in side elevation, presents at a point just back of the pommel a curve or an incline downward from said pommel which is nearly parallel with the line *p* at the top of said pommel.

I claim—

The design for a saddle-tree which consists, essentially, of a saddle-tree with backwardly and downwardly inclined center line, *p*, at the top of the pommel, and having the vertical line *b* at the front of the pommel, terminating at the line *d* and forming an angle therewith, said line *d* curving forwardly and downwardly, then backwardly and downwardly, as at *f*, then upwardly, as at *g*, then downwardly, as at *h*, then upwardly, as at *j*, then forwardly, as at *k*, to the cantle, the series of curves making one continuously-curved outline from the point *e* to the point *k*, as described and shown.

In testimony that I claim the foregoing I have hereunto set my hand this 19th day of August, 1886.

JOSEPH BEVAN.
